 Baden, Switzerland

Application February 8, 1940, Serial No. 317,946
 In Germany May 6, 1938

4 Claims. (Cl. 200—148)

This invention relates to electrical circuit breakers and particularly to heavy duty switching systems including a circuit breaker and a disconnect switch that are operated, in proper sequence, by air under pressure and in which an air blast passes over or between the circuit breaker contacts to extinguish the arc.

Protective switching systems of this type for use on lines carrying heavy currents have previously required contacts of large dimensions at both the circuit breaker and the disconnect switch, and the switches were of relatively heavy constructions. It has been proposed to bridge a current-carrying switch across the circuit breaker and disconnect switch to carry the normal load current. This arrangement is open to the objection that it materially increases the time required for an opening of the switch system;—it being necessary to open the current-carrying switch, then the circuit breaker, and finally the disconnect switch. The prior switch systems were thus characterized by a relatively long operating time when a third switch was bridged across the circuit breaker and disconnect switch or by circuit breaker contacts in which the number and size of the multiple section contacts for carrying the high load current interfered with the air blast that was to extinguish the arc.

An object for the present invention is to provide an electric circuit breaker having contacts of such design that the entire rated current may be carried by the circuit breaker, an air cylinder and piston for holding the contacts in engagement under such pressure that the load current is carried without undue heating, and valve mechanism for supplying air under pressure to the other end of the cylinder to open the contacts. An object is to provide a circuit breaker of the type stated in which the contacts take the form of a fixed annular or nozzle contact and a movable blade or plunger contact which seats upon the nozzle contact when the circuit breaker is closed, the contacts being located in a chamber that is normally under atmospheric pressure and in communication with that end of the cylinder to which pressure air is supplied to open the circuit breaker, and the valve mechanism includes a valve operable upon the introduction of pressure air into the chamber to vent the opposite end of the cylinder to atmosphere.

These and other objects and advantages of the invention will be apparent from the following specification when taken with the accompanying drawing in which the single figure is an eleva-

tion, with parts in section, of a circuit breaker embodying the invention.

The grounded supporting frame 1 of the circuit breaker system carries a tank 2 in which compressed air is stored, a main blow or control valve 3 for controlling the flow of the pressure air to the operating mechanism, and hollow insulators 4, 5 that support the circuit breaker. The blow valve is actuated in the usual manner, for example by a piston 3a to which pressure air is admitted by a pilot valve 3b. The casting or body member 6 which is carried by the insulator 5 has an air passage 7 that extends from the hollow insulator 4 to the upper surface of the casting. An air chamber is formed above the casting 6 by an insulating cylinder 8 that carries a hollow casting 9 that constitutes one terminal of the circuit breaker. A contact 10 on the terminal casting 9 has the form of a nozzle which presents a round surface for engagement by the domed contact 11 on the upper end of the switch blade or plunger 12.

The plunger 12 extends through the body member 6 and has a flange or piston 13 that slides in a cylinder 14 in the lower portion of the member 6. A port 15 connects the upper end of the cylinder 14 to the air passage 7, and a vent at the lower end of the cylinder is controlled by a valve 16 that is slidable in the member 6 and carries a piston 17 that is normally held in raised or vent-closing position by a spring 18. The valve 16 and piston 17 are both acted upon by the pressure within the lower end of the cylinder, and the valve assembly is therefore balanced or approximately balanced against this pressure but not against pressure exerted on the upper face of piston 17.

The lower end of the cylinder is closed by a casting 19 that is carried by the insulator 5, and a passage 20 extends through the casting 19 to supply pressure air to the lower face of the piston 13. A measuring orifice or throttle member 21 is inserted in the passage 20 to limit the flow of air when the vent valve 16 is open.

The lower end of the circuit breaker blade 12 has leaf contacts 22 for engagement by the disconnect switch blade 23 that is pivotally supported on the insulator 24 and moved to open position by link 25 and a pressure cylinder 25' after the circuit breaker is opened. A strap 26 on insulator 24 serves as the second terminal for the switch assembly.

The parts are illustrated in their normal closed positions and the circuit extends from terminal strap 26 and the disconnect switch 23, 22, through

the circuit breaker blade 12, contacts 11 and 10, to the other terminal 9. The upper end of the cylinder is at low or atmospheric pressure and the contacts 10, 11 are held in engagement by pressure air that enters the lower end of the cylinder 14 through the passage 20 and hollow insulator 5. The rounded surfaces of the contacts restrict the contacting area to approximately a line and the high pressure engagement affords a low resistance contact capable of carrying heavy currents without undue heating.

The main valve 3 is actuated to admit high pressure air to passage 7 when the circuit breaker is to be opened. The high pressure air passes to the upper end of the cylinder 14 through the port 15 and also acts on the small piston 17 to open the vent valve 16. The piston 18 is forced downwardly to separate contact 11 from the fixed contact 10, and the arc is extinguished by the blast of air that passes over the tip of contact 11 to escape through the nozzle contact 10. The throttle member 21 restricts the flow of air to the lower face of piston 18 and a rapid opening of the circuit breaker is obtained whether or not a valve is employed to close the passage 20. The disconnect switch 23 is preferably opened automatically in timed relation to the opening of the circuit breaker but the mechanisms for this operation are not shown as they form no part of the present invention.

The disconnect switch is of course closed again before valve 3 is adjusted to vent the pressure air from the upper end of the cylinder and the chamber which encloses the contacts. As illustrated, the mechanism for operating the disconnect switch may comprise pipes 27, 28 for admitting pressure air to the opposite ends of the cylinder 25; the pipe 27 leading to the low pressure side of the blow valve 3 and the flow through pipe 28 being controlled by a valve 29.

It is to be understood that the described construction is illustrative of the invention and that various changes may be made in the parts, their sizes, shapes and relative arrangements without departure from the spirit of my invention as set forth in the following claims.

I claim:

1. A circuit breaker comprising means defining an arc-extinguishing chamber, a nozzle contact carried by one wall of the chamber, a sliding member having a domed contact for seating against said nozzle contact, a cylinder and piston supporting said sliding member for movement axially of the chamber, means for continuously

admitting air to one end of the cylinder to displace said piston to hold said domed contact in firm engagement with said nozzle contact, a port connecting the other end of the cylinder to said chamber, means responsive to pressure within said chamber to vent the first end of the cylinder, and valve means for admitting pressure air to said chamber.

2. A circuit breaker as claimed in claim 1, wherein said venting means comprises a second piston slidable in a wall of said chamber, and a vent valve carried by said second piston, the pressure within the chamber being exerted on the outer face of the second piston and the pressure within the first end of the cylinder being applied in opposite directions to said second piston and valve.

3. A circuit breaker comprising a reciprocating blade member, a piston carrying said member and movable in a cylinder, a tank for storing air under pressure, a contact on one end of the blade member, a fixed contact in line with said blade member contact, a permanently open air passage connecting said tank to the end of said cylinder opposite said contacts, means in said passage restricting the flow of air therethrough, valve means and a second passage for supplying pressure air from the tank to the other end of the cylinder, and pressure-responsive vent means operable by pressure air admitted to said other end of the cylinder to vent to atmosphere the first end of the cylinder.

4. A circuit breaker adapted to carry heavy currents comprising a body structure including a cylinder, a sliding member extending through said cylinder and carried by a piston slidably in the cylinder, a contact on one end of the sliding member, a nozzle contact in fixed position in the path of said sliding member contact when the piston is moved in one direction, means for admitting air under pressure to one end of the cylinder to move the piston to engage the contacts and hold the same in contact under pressure, a chamber enclosing said contacts, means for admitting pressure air to said chamber and to the other end of said cylinder, and means operable by pressure air in the chamber for venting the first end of the cylinder, thereby to move the piston in the opposite direction to separate said contacts and to extinguish the arc by the flow of air from said chamber through said nozzle contact.

HANS THOMMEN.
